United States Patent Office

Des. 218,443
Patented Aug. 18, 1970

218,443

POULTRY COOP

K. Zack Taylor, Decatur, Ga., assignor to Uniplastic Corporation, Atlanta, Ga., a corporation of Georgia

Filed June 11, 1968, Ser. No. 12,298

Term of patent 14 years

Int. Cl. D30—01

U.S. Cl. D30—1

Fig. 2

FIG. 1 is a perspective view of a poultry coop, showing my new design; and

FIG. 2 is a bottom view thereof.

The rear sidewall, not shown, is the same in appearance as the front sidewall, and the right-hand sidewall, not shown, is the same as the left-hand sidewall.

I claim:

The ornamental design for a poultry coop, substantially as shown and described.
